UNITED STATES PATENT OFFICE.

ALBERT H. BATES, OF ELGIN, ILLINOIS, ASSIGNOR, BY MESNE ASSIGNMENTS, TO THE HOOVER COMPANY, OF NORTH CANTON, OHIO, A CORPORATION OF OHIO.

SWITCH.

Application filed August 5, 1922. Serial No. 579,803.

To all whom it may concern:

Be it known that I, ALBERT H. BATES, a citizen of the United States, residing at Elgin, in the county of Kane and State of Illinois, have invented certain new and useful Improvements in Switches, of which the following is a specification.

This invention relates in general to improvements in electric switches and refers in particular to a novel single push button type of switch in which the electrical circuit controlled by the switch is either opened or closed by the movement of a single push button, which actuates a snap mechanism carrying the movable contact elements of the switch. After each movement of the push button, the contact elements of the switch remain in the position to which they have been thrown and the push button returns to the normal position for the next movement which throws the contact elements to another position.

My invention may be applied generally to the light and power circuits commonly used for the distribution of electrical energy, and is especially adaptable for use in connection with machines or apparatus in which the location of the switch is necessarily or preferably such as to be inconvenient to be operated by hand, but is adapted to be operated by foot pressure. My invention, however, is by no means limited to this type of machine or apparatus or this mode of operation.

An object of my invention is to provide a snap action switch which is compact, rugged, and simple in construction.

Another object of my invention is to provide a novel form of snap action which possesses the quickness and reliability of action necessary to safe handling of relatively heavy currents.

Another object of my invention is the provision of novel and reliable means for actuating the snap action.

Other objects will appear from the following detailed description and in the claims appended hereto.

In the accompanying drawings:

Figure 1 is a horizontal sectional view of

a switch made in accordance with my invention, taken on line $x-x$ of Fig. 2 looking in the direction of arrows.

Figure 2 is a vertical sectional view taken on line $y-y$ of Fig. 1 with parts shown in elevation.

Figure 3 is a vertical sectional view taken on line $z-z$ of Fig. 1 with parts shown in elevation.

Figure 4 is an axial sectional view with parts shown in elevation illustrating a modified form of actuating mechanism.

Figure 5 is a sectional view taken on line $w-w$ of Fig. 4 with parts shown in elevation.

Figure 6 is a sectional view on line $v-v$ of Figure 1.

Figure 7 is a detail view.

In Figures 1 to 3 inclusive I have illustrated a preferred embodiment of my invention, which may for ease of description be considered as constituted of two elements; viz a snap action mechanism and an actuating mechanism which mutually coact and combine to form a switch.

Both the snap action and the actuating mechanism are supported upon a base 10 made of any suitable non-conducting material which also carries the electrical connections, a metal cover 11 and an insulating lining 12.

The base 10 is preferably made of a general cylindrical shape formed with a central aperture 13 which encloses and protects the snap action.

The base is further provided with two upstanding post portions 14, 14 upon which the entire switch mechanism rests.

In the modification illustrated in Figures 1 to 3 inclusive the snap action is suspended in the central aperture 13 of the base 10 by means of a U-shaped supporting frame 15 having outwardly bent end portions 16, 16 resting on the posts 14, 14 provided with screw threaded holes engaging the screws 17, 17 which pass through the base 10 and are received in nuts 18, 18 which also secure in place the anchorage members 19, 19.

The nuts and anchorage members are situated in cutaway portions 20, 20 of the base

10 and the anchorage members receive the screws 21, 21 which hold the metal cover 10 and the insulating lining in position.

The side portions of the supporting frame 15 below the end portion 16, flare outwardly as shown at 22, 22 for a purpose that will be described later and are also formed with bent lugs 23, 23 which act as stops for the pole piece.

10 Mounted in the side portions of the frame is a short shaft 24 on which are pivotally mounted the cams 25, 25 which in this modification are connected on one side by an integral portion 26 in order to stiffen and 15 maintain the cams in proper registry.

Each cam is formed with a wedge shaped upper end having side faces 27, 27 which meet at the point 28 and terminate at the other ends in the shoulders 29, 29.

20 Beneath the shaft 24 each cam is provided with an arcuate slot 30 through which passes a pin 31 mounted in the side portions of the frame 15 and upon which is pivotally mounted the U-shaped pole piece 32. The 25 side arms of the pole piece swing outside of the cams 25, 25 and have their range of movement limited by the stops 23, 23. The bottom of the U-shaped pole piece is perforated at 33 and is further provided with 30 an extension having formed thereon lugs 34, 34 which clamp and secure a strip of insulation 35 to which the resilient movable contacts 36, 36 are secured by means of a rivet 37. By this construction the mechanism of 35 the switch is insulated from the electrical currents and the maximum protection is given the operator.

The cams 25, 25 are each provided with an aperture 38 which register with each 40 other and pivotally receive the integral lugs 39, 39 formed on the head 40 on one end of the guide member 41 (Fig. 7), the lower end of which extends through the perforation 33 in the bottom of the pole piece. 45 Around the guide member, between the head 40 and the bottom of the pole piece is a coiled compression spring 42.

From the drawings and the description it 50 will be seen that when the cams 25, 25 are rotated on the shaft 24 so that the points 28, 28 cross a vertical plane through the shaft 24, the spring 42 is compressed and when the pivot lugs 39 cross the line connecting the aperture 33 and the shaft 24, the 55 pole piece 32 is thrown to the other side of the switch with a quick snap action. A reverse rotation of the cams causes the pole piece to be thrown with a snap action in the opposite direction.

60 In order to provide a simple and efficient means for giving the required motions to the cams 25, 25 I have provided an actuating mechanism comprising a centrally apertured supporting ring 43 formed with an upturned flange 44 and laterally extending ears

44'. A guide tube 45 is provided at the lower end with laterally extending ears 46, similar in shape to the ears 44', rests upon the ring 43 and together with the ring is secured to the frame 15 by means of the 70 screws 17, 17.

It will thus be seen that the screws 17, 17 which engage the threaded holes in the ends 16, 16 of the frame 15 will secure the snap action mechanism and the actuating mechanism together so that they form an assembly that can be removed from the base 10 as a unit. This construction facilitates assembling of the switch as well as inspection at any time.

On diametrically opposite sides the guide tube is provided with slots 47, 47 which receive and guide lugs 48, 48 formed integral with the cylindrical plunger 49 which is closed at one end and forms the push button 80 of the switch.

Resting upon the ring 43 and centered by the upturned flange 44 is a helical compression spring 50 which extends to the closed top of the plunger 49 where it is bent radially inward as at 51 and then downwardly coaxially with the plunger as at 52 to a point approximately level with the supporting ring 43. At this point the spring wire is bent at right angles at 53 and then back 95 on itself to form a terminal 54 which is parallel to the shaft 24 and long enough to bridge across the cams 25, 25. Due to the resiliency of the spring wire, the portion 52 tends always to remain coaxial with the plunger 49 and automatically returns to this position after each actuation of the switch when the plunger is allowed to assume its normal position under the influence of the spring 50.

To coact with the movable contacts 36, 36 I have provided the fixed contacts 55, 55 (see Fig. 6) which are provided with horizontally extending portions threaded to engage the screws 56, 56 which pass through the base 10 and secure the contacts in position. The lead in wires are connected to the contacts 55, 55 by means of the nuts 57, 57.

In Figures 4 and 5 I have illustrated a modified form of actuating device in which the guide tube 58 is provided at the upper end with a portion 59 of reduced diameter which guides the plunger 60 and limits its upward travel by engaging with the enlarged lower end 61.

The lower end of the guide tube is provided at diametrically opposite points with laterally extending ears 62, 62 each having an aperture therein.

The guide tube 58 is secured on the supporting ring 63 by means of bolts 64 and nuts 65. The bolts 64 passing through the ears 62, 62 and through similar ears formed on the supporting ring.

The centrally apertured supporting ring 130

63 is also provided with laterally extending ears 66 having screw threaded holes which receive the screws 67 and with an upturned flange 68 which centers a helical compression spring 69 one end of which bears against the ring 63 and the other against the shoulder 61 of the plunger 60.

In the upper closed end of the plunger 60, a securing member 70 is fixed by any desirable method such as a tight push fit or by welding. This member is circular in shape and is provided with two loops 71 which receive and pivotally support the trunnions 72 of the push bar 73 which extends through a hole in the member 70 and comprises a flat strip formed with a rounded lower end 74 and an oblong aperture 75 having a beveled lower edge 76. The push bar is made sufficiently wide to open the distance between the cams 25, 25 and when the plunger is depressed the lower rounded end follows one of the side faces until it reaches a shoulder 29 whereupon further depression of the plunger causes rotation of the cams. During this operation the push bar assumes a position at an angle to the axis of the plunger and in order to return the push bar to its normal coaxial position, irrespective of the position in which the switch mechanism may be mounted, I have provided two flat leaf springs 77, 77 fastened at diametrically opposite points to the under side of the supporting ring 63 by means of the bolts 64 and the nuts 65 and having their free ends extending through the aperture 75 and normally pressing against the bevelled lower edge 76.

In this modification it will be noted that the supporting frame in which the snap action is mounted is made of two members 78, 78 each of which has a laterally extending end portion 79 with holes to receive the screws 67, 67.

At the lower end each member 78, flares outwardly and is provided on each side with a stop lug 80 which limits the movement of the pole piece.

Operation.

When the plunger 49 is depressed, the terminal 54 of the resilient spring wire contacts with the sloping side face 27 of the cam 25 which happens at that time to be presented. Further depression of the plunger causes the terminal of the spring wire to slide along the face 27 until it reaches the shoulder 29, whereupon the cams 25 are rotated about the axis of the shaft 24. This rotation of the cams causes the lugs 39 to travel in a path which crosses a vertical plane through the axis of the shaft 24. As soon as the lugs 39 have crossed the line connecting the aperture 33 with the axis of the shaft 24, the spring 42, which has been compressed by this action, throws the pole piece 32 with a quick snap

action to the other side of the switch where it is stopped by the lugs 23 on the supporting frame 15.

The compression of the spring 42 not only tends to hold the pole piece in the position to which it has been thrown, but also holds the cams 25 in their extreme position so that when the plunger is again depressed the terminal of the spring wire will contact with the other face 27 and on further depression of the plunger cause a movement of the switch, which is exactly similar but opposite in direction to that just described.

During its entire excursion of travel the terminal 54 is guarded from any undue movement longitudinally of the shaft 24 by the flaring portions 22, of the supporting frame 15 which conform to the path of travel of the terminal 54.

When pressure is removed the plunger under the influence of the spring 50 returns to the normal position and the portion 52 of the spring wire which carries the terminal 54 automatically assumes a position coaxial with the plunger due to the resiliency of the material.

In the modification shown in Figures 4 and 5, the switch is actuated in the same manner as described. On depressing the plunger the push bar 73 engages the faces 27 of the cams 25 which happen to be presented at that time, and in the manner just described rotates the cams and thereby causes a snap action to be imparted to the pole piece. Upon the return of the plunger 60 to its normal position under the influence of the spring 69, the flat leaf springs 77 engage the lower bevelled edges of the aperture in the push bar and force it to assume a position which is coaxial with the plunger irrespective of the position in which the switch is mounted. It is also to be noted that the arcuate slots 30 in the cams 25 act as stops for the cam by reason of the ends engaging the pin 31 at each end of the travel of the cam. It will thus be seen that both the cams and the pole pieces are provided with stops and that both will be held in either of their extreme positions by the action of the compression spring 42.

I claim:

1. In a device of the character described, an actuating mechanism comprising a guide member, a plunger guided by said guide member and a coil of resilient material normally tending to force said plunger in one direction and having an extension normally coaxial with said plunger.

2. In a device of the character described, an actuating mechanism comprising a guide member, a plunger guided by said guide member and a coil of resilient material normally tending to force said plunger in one direction and having an extension normally coaxial with said plunger, said extension be-

ing provided at the free end wth lateral projections.

3. In a switch, the combination of an actuating mechanism comprising a plunger and an element tending automatically to remain coaxial with said plunger, with a snap action mechanism comprising a supporting frame, a pole piece pivotally supported by said frame, two spaced operating cams enclosed by said pole piece and supported from said frame, and a guide member and a compression spring supported jointly by said cams and the pole piece.
4. In a switch, the combination of a snap action mechanism comprising a supporting

frame, a pole piece pivotally supported by said frame, two spaced operating cams supported from said frame and enclosed by said pole piece and a guide member and a compression spring supported jointly by said cams and the pole piece with an actuating mechanism comprising a plunger and an element tending automatically to remain coaxial with said plunger and adapted to engage simultaneously the operating cams. 25

Signed at Chicago, in the county of Cook, and State of Illinois, this 28th day of July, A. D. 1922.

ALBERT H. BATES.
